UNITED STATES PATENT OFFICE

ALBERT J. GELOW, OF THREE OAKS, MICHIGAN, ASSIGNOR TO THE WARREN FEATHER-BONE CO., OF THREE OAKS, MICHIGAN, A CORPORATION OF MICHIGAN

HOSE SUPPORTER

Application filed July 28, 1930. Serial No. 471,160.

This invention relates to hose supporters, and more particularly to supporters for children's use.

The object of the invention is to provide a supporter calculated to promote greater security and comfort by providing a two-point button attachment coupled with ample resiliency, permitting freedom of movement without the usual adjustments in the form of 10 metallic buckles and parts which ordinarily contact with the body.

A further object of the invention is to provide a hose supporter designed to eliminate the use of the familiar safety pin as the 15 method of attaching the supporter to the child's garment, and thus avoid the tearing thereof or the unguarding of the pin in the event of excessive strain at the single point of attachment.

20 Other advantageous features of the invention are hereinafter disclosed in connection with the accompanying drawing, in which

Figure 1 is a general view of the supporter showing the manner in which it is attached 25 to a child's garment and supports the hose or stocking, and

Figure 2 is an enlarged view of the supporter showing the detail of its construction.

The supporter comprises two main or essential parts, namely, a lower portion in the form 30 of an inverted V-shaped band 1 provided at the end of each branch with the usual type of hose-engaging fastener 2, 2 and the upper resilient portion 3, the two portions being joined at their apexes. The lower portion preferably consists of a strip of non-elastic 35 tape or ribbon-like fabric folded intermediate its ends, and stitched together transversely as at 4 with the branches spread in V-form so as to form a loop 5 at its top, 40 preferably reinforced by an inner sleeve 5a of the same tape bound by a strip of adhesive tape.

The upper portion 3 is preferably made of 45 double strands of a fabric-covered elastic cord. A single length of this cord fastened at its ends and doubled, and then inserted through the loop 5 of the non-elastic lower portion, so that the projecting ends are of the 50 same or substantially the same length. The

connection between the ends of the elastic cord is preferably located so that it is enclosed within the loop 5 when the parts are assembled and thus concealed from view. To secure the elastic cord in place, a metal 55 band 6 is clamped tightly around the four strands which are brought together to form an elastic loop 7 linked with the loop 5 of the lower non-elastic portion 1. The free ends of the double elastic cord are converted into 60 small loops 8, 8 by fastening the two strands together a short distance from the ends as by metal bands 9, 9; these loops being adapted to be fastened over buttons attached to the child's garment.

Thus as shown in Figure 1, children's clothing is usually made with buttons 10, spaced about the waist band on the underclothing, shirt or blouse, for retaining the lower outer garment, either trousers or skirt. Thus the 70 looped ends of the elastic upper portions may be readily attached to pairs of such waist buttons spaced apart forwardly of the region of the hips, so that it is ordinarily unnecessary to provide separate buttons for the suspension of the supporters.

Obviously the strain is divided between the two points of attachment and the elasticity of the strands permits the proper distribution of the strain with the movement of the 80 body and thus affords the proper support for the hose without discomfort. Moreover the double elastic strand attached at points spaced apart makes it unnecessary to provide for the lengthening and shortening of 85 the supporter by the use of buckles as is necessary in the ordinary single elastic strand pin-attached type of supporter. It will be understood, however, that it is not intended that one size of support will serve for all ages 90 and sizes of children, but rather that graduated sizes will be provided, differing chiefly in the length.

Having set forth a preferred embodiment of my invention, I claim:

1. A hose supporter comprising a lower portion consisting of a band of non-elastic tape folded upon itself intermediate its ends and stitched to provide a loop, fasteners secured to the ends of said tape and an upper 100

portion consisting of double strands of elastic cord passing through said loop and fastened together to form a complementary loop, the free portions of said strand being of substantially equal length and provided with looped ends adapted for attachment to buttons secured in spaced relation at the waist of a garment.

2. A hose supporter comprising a length of 10 tape doubled upon itself and stitched to provide a top loop and diverging branches having fasteners at their ends, and a strand of elastic cord passing through said loop and doubled and fastened to provide a complementary loop and diverging branches having looped ends adapted for attachment to buttons secured in spaced relation about the waist of a garment of the wearer.

3. A hose supporter comprising a length 20 of tape folded upon itself in V-form and stitched to provide a central loop and branches having hose-engaging fasteners at their ends, a reinforcing sleeve inserted in said loop, and a double strand of elastic cord 25 passing through the reinforced loop of said tape and metal binders applied to said strand to form a central loop and end loops, the latter adapted to engage waist buttons on the garment of the wearer.

30 Signed at Three Oaks, Michigan, this 23d day of July, 1930.

ALBERT J. GELOW.
